UNITED STATES PATENT OFFICE.

RUFUS KING, OF PLAINVILLE, MASSACHUSETTS, ASSIGNOR TO BUGBEE & NILES CO., OF PROVIDENCE, RHODE ISLAND, A CORPORATION OF RHODE ISLAND.

LINK FOR EXPANSIBLE BRACELETS.

1,141,552.

Specification of Letters Patent. Patented June 1, 1915.

Application filed November 14, 1914. Serial No. 872,120.

To all whom it may concern:

Be it known that I, RUFUS KING, a citizen of the United States, residing at Plainville, in the county of Norfolk and State of Massachusetts, have invented a new and useful Improvement in Links for Expansible Bracelets, of which the following is a specification.

This invention relates to certain new and useful improvements in links for expansible bracelets, and the primary object of the invention is to provide a link structure which has novel and improved means for securing the two parts of the link together.

15 A further object of the invention is to provide means for locking the two parts of the link in position, which enables the locking of the parts to be easily and quickly effected thus saving time and expense in the 20 assemblage of the links.

In the drawings—Figure 1 is a side elevation of the two parts of the bracelet link showing the same in the act of being connected. Fig. 2 is a section view of the link 25 in its completed form taken on the line 2—2 of Fig. 3. Fig. 3 is a section on the line 3—3 of Fig. 2, and Fig. 4 is a section on the line 4—4 of Fig. 2.

The two parts 1 and 2 of the bracelet 30 link may be of any desired form, and are here shown of the trough-like type. To one end of the part 1 is soldered a tubular post 3, which may be formed of hollow wire, while a similar post 4 is soldered to the 35 opposite end of the part 2. The opposite end of the part 1 has a pin 5 soldered thereto while the other end of the part 2 has a similar pin 6 soldered thereto. The tubular

posts are formed with openings 7 located adjacent to the inner ends of the posts and 40 on the inner sides of the latter, while the pins are formed of malleable material and have their ends tapered and curved inwardly as at 8, so that when the two pins are placed within the tubular posts and the 45 two posts are forced together, the tapered points of the pins, due to the malleability of the metal of which the pins are formed, will be bent and forced through the apertures 7 by reason of the fact that the curved 50 ends of the pins engage with the opposite parts 1 and 2 respectively. It will thus be seen that the points 8 of the pins are forced through the apertures 7 and project through said apertures, thus being clenched to the 55 tubular posts resulting in locking of the pins to the posts so as to prevent separation of the parts.

Having thus described my invention, I claim as new and desire to secure by Letters 60 Patent:—

In combination with the two parts of a bracelet link, a hollow post on one of the parts and rigidly secured at its inner end to said part, said post having an aperture adjacent its inner end and on its side, and a tapered malleable pin borne by the other part and receivable in the post and having its point extending through the aperture.

In testimony whereof I have signed my 70 name to this specification in the presence of two subscribing witnesses.

RUFUS KING.
